UNITED STATES PATENT OFFICE.

HUBERT A. HOLTFRERICHS, OF DODGE CITY, KANSAS.

END-GATE.

1,041,794.

Specification of Letters Patent.

Patented Oct. 22, 1912.

Application filed January 27, 1912. Serial No. 673,754.

To all whom it may concern:

Be it known that I, HUBERT A. HOLTFRERICHS, a citizen of the United States, residing at Dodge City, in the county of Ford 5 and State of Kansas, have invented certain new and useful Improvements in End-Gates, of which the following is a specification, reference being had to the accompanying drawings.

10 My invention relates to new and useful improvements in end gates and more particularly to a locking means therefor, and my object is to provide a device of this character which will securely retain the end gate 15 in locked position and which will permit of being quickly and readily operated when it is desired to open the gate.

A further object of the invention resides in providing a locking bar mounted in bearings 20 on the end gate and adapted to partially rotate therein, said locking bar having the ends thereof bent or offset from the general trend of the bar and a still further object resides in the provision of an arm 25 on the bar which will permit of being swung to oscillate or partially rotate the bar in its bearings.

A further object of the invention is to provide a pivoted lever on said arm and a 30 still further object resides in providing a spring member in the path of said lever to retain the lever in its effective position.

Still another object of the invention resides in providing a device which is extremely simple and durable in construction, 35 inexpensive to manufacture, and one which will be very efficient and useful in operation.

With these and other objects in view, my invention consists in the novel features of 40 construction, combination and arrangement of parts as will be hereinafter referred to and more particularly pointed out in the specification and claims.

In the accompanying drawing, forming a 45 part of this application, Figure 1 is a fragmentary perspective view of a wagon showing my improved end gate applied to use thereon, and Fig. 2 is a section through the end gate showing the application and operation of the spring member thereon.

In carrying out my invention I shall refer to the drawing in which similar reference characters designate corresponding parts throughout the several views and in 55 which—

1 indicates a wagon body of any desired

type, but preferably such as used in connection with grain wagons, having secured to the inner faces of the sides of said body at the rear ends thereof, the vertical securing 60 or bracing strips 2 and secured to these strips 2 is the end board 3. This end board 3 has formed therein the end gate 4, which is adapted to swing outwardly from its upper end, the same being hinged at its upper 65 end to the end board by means of the hinges 5 and the side edges of the gate 4 are inclined outwardly from their upper to their lower ends, as shown at 6.

Mounted on the rear faces of the end 70 gate 4, adjacent the lower edge thereof, are the bearings 7, within which is mounted and designed to partially rotate therein, a rod or bar 8, said bar having the extremities thereof bent or offset, as shown at 9, and 75 extended beyond the front face of the strips 2 and secured on the strips 2, adjacent the lower ends thereof, are the straps 10, which are bent outwardly to form keepers for the aforesaid ends 9 of the bar 8. These 80 straps or keepers 10 are so disposed on the strips 2 that when the bar is in one position, the offset portions 9 thereof will be disposed immediately under said keepers to prevent the end gate from being swung outwardly, 85 while when the rod or bar 8 is partially rotated in another position, the ends 9 thereof will be disposed below the free ends of said keepers, whereby said gate may be swung outwardly and in order to provide for the 90 partial rotation of said bar 8 and the securing of the same in its effective position, I provide an arm 11, which is rigidly secured to the bar and when disposed in its vertical position, as shown in Fig. 1, will dispose 95 the opposite portions 9 immediately in the rear of and contacting with the keepers 10.

Pivoted on the outer end of the arm 11 is a hand lever or the like 12 which, when moved into horizontal position, as 100 shown in Fig. 1, is adapted to be received in an upwardly facing keeper 13, carried on the outer face of the gate 4 and a leaf spring 14, secured at its upper end to the end gate, is disposed vertically thereof and in the path 105 of said hand lever. This leaf spring 14, secured at its upper end, has the lower portion thereof bent outwardly from the face of the end gate and the lower end of said spring member is disposed in substantial alinement 110 with the keeper 13, so that it will be obvious that as the lever 12 is swung in the one direc-

tion toward the keeper 13, a portion of said lever will contact with the spring 14 and cause the said lever to bind tightly between said keeper and spring at the same time causing the spring to yield. The lever may be swung until the same has completely passed beyond the lower end of the spring, whereupon the latter will again spring outwardly and said handle member will rest in the keeper 13, thus retaining the device in its adjusted position, whereby it will be appreciated that the gate may not be casually opened.

In practice, should it be desired to open the end gate to remove the contents of the wagon, the operator first forces the lower end of the spring 14 inwardly, whereupon the lever 12 is swung upwardly over the upper face of said spring member to such point as to entirely release the same from its engagement with the keeper 13 and at this point the lever may be swung outwardly which will swing the arm 11 outwardly and cause the rod or bar 8 to be partially rotated in its bearings. The partial rotation of the bar in its bearings will dispose the offset or bent extremities 9 below the lower ends of the keepers 10, whereby the end gate may be readily swung outwardly and the contents of the wagon removed.

From the foregoing it will be seen that I have provided a simple, inexpensive and efficient means for carrying out the objects of the invention and while I have particularly described the elements most well adapted to perform the functions set forth, it is obvious that various changes in form, proportion and in the minor details of construction may be resorted to without departing from the spirit or sacrificing any of the details of the invention.

Having thus described my invention, what I claim is:—

1. The combination with a wagon body and an end gate hinged thereto; of a bar carried on said end gate and partially rotatable thereon, said bar having the extremities thereof bent and extended beyond the

side edges of said end gate, a pair of strips carried on the rear end of the wagon body 50 beyond the side edges of said end gate, said strips having the lower portions thereof bent outwardly and adapted to receive in engagement with the same, the bent extremities of said bar when the latter is disposed in one 55 position, a rigid arm carried on said bar, a pivoted lever carried on said arm, a keeper carried on the end gate and adapted to receive said lever therein, and a leaf spring member also carried on the end gate in the 60 path of said lever, said spring member being adapted to retain the lever in locked position under the keeper.

2. The combination with a wagon body having an end gate thereon; of a locking bar 65 carried on said end gate and partially rotatable thereon, the ends of said locking bar being offset and extended beyond the side edges of the end gate, a pair of strips carried on the rear ends of the wagon body 70 adapted to receive the offset ends of said locking bar thereunder, when said bar is disposed in one position, a rigid arm carried on said bar for the operation of the latter, said arm being adapted to rest flatly 75 against the end gate when the locking bar is disposed in its locking position, a lever pivoted to the outer end of said arm, an upwardly facing keeper secured on the outer face of said end gate and adapted to receive 80 said lever therein, and a leaf spring secured at its upper end to the outer face of said end gate in the path of said lever toward the keeper, the free end of said leaf spring being bent outwardly from the face of said 85 end gate and terminating in substantially the same plane as that in which the keeper is disposed, whereby said lever may be retained in its locked position within the keeper.

In testimony whereof I hereunto affix my signature in the presence of two witnesses.

HUBERT A. HOLTFRERICH.
